WAXWORK, ROBOT, AND LIKE FIGURES

Filed Sept. 14, 1929

UNITED STATES PATENT OFFICE

EDWARD JONATHAN MARRIOTT, OF LONDON, AND CYRIL FRENCH, OF KINGSTON-ON-THAMES, ENGLAND

WAXWORK, ROBOT, AND LIKE FIGURES

Application filed September 14, 1929, Serial No. 392,638, and in Great Britain October 4, 1928.

This invention relates to improvements in the disposition of the parts of telephone equipments, and is particularly applicable to installations wherein it is desired to provide calling stations which will readily attract the attention of would-be users.

The object of the invention is to provide such an equipment which will require the minimum amount of skill to use and which will enable a single operator at a remote point to answer enquiries from each of a number of stations while creating to some extent an illusion of personal attention at the calling stations.

15 In accordance with the invention, such a telephone equipment consists of a device representing or caricaturing a human being situated at a number of communicating stations and furnished with a loud-speaking telephone arranged so as to create the illusion that the figure itself speaks and with a microphone.

20 In order to establish communication from a communication station, a calling device incorporated in the figure is operated. In its preferred form, this device consists of a press-button which when operated closes an electric circuit and thereby produces a signal to the attendant at a central station who 25 thereupon makes the necessary connections.

The microphone receives the words of the caller which are transmitted to the central station in any suitable way, for instance through an electrical circuit and an amplifier to a receiver at the central station. 30 Similarly, a transmitting device at the central station is connected to the loud-speaking telephone through a like arrangement so that the attendant's words are reproduced in life-like manner by the figure at the communicating station.

Such an arrangement is particularly useful at exhibitions, large stores, etc. where people are constantly needing information. 35 One of its chief advantages is that the reply is made audible to all who happen to be in the vicinity and in order to increase this advantage still further, the back of the head of the figure may form a sounding board.

40 The figure may also be provided with a

device of any suitable design which will indicate to the caller that communication with the central station has been established.

In order that the invention may be clearly understood and readily carried into effect, 55 a system arranged in accordance with the invention will now be described with reference to the accompanying drawings, wherein:—

Figure 1 shows diagrammatically one of the figures and the circuit connections to 60 that figure from the attendant's apparatus and the branch lines to three other figures; while

Figure 2 is a diagram of connections of the attendant's apparatus which can be 65 plugged into the main wiring.

In these drawings, the figure shown at A is a grotesque human figure intended to follow the popular conception of a "robot". It may be carried out in waxwork or in 70 painted wood or other material, for as will be seen, it is not a figure made up of complicated surfaces. It is shown with a loud-speaking telephone receiver in the head shown conventionally in dotted lines at S behind the 75 mouth of the figure. A transmitting microphone is shown conventionally in dotted lines at M embodied in the chest of the figure, while in the neighbourhood of the waist is shown a press-button switch P for calling purposes. 80

The press-button switch is connected to complete, through conductors a^1 and b^1 , the circuit of a battery B through an indicating lamp L^1 . The battery B and the lamps are placed at the attendant station so that when 85 anyone presses the push switch P, the lamp L^1 will light up and call the attendant's attention. The system illustrated is wired to accommodate four figures, and there is similar wiring to each of the figures; for example, there are conductors a^2 and b^2 going to the push-button switch in the second figure which is not shown. Similarly, there are conductors a^3 and b^3 for the third figure, and conductors a^4 and b^4 for the fourth figure. The attendant's switchboard K, besides carrying the lamps L^1 , L^2 , L^3 , L^4 , has four sets of sockets F^1 , F^2 , F^3 , and F^4 , each set 90 comprising four sockets spaced apart so that 95

they can be engaged by the four plugs G belonging to the attendant's apparatus.

For convenience of description, the plug G can be assumed to be plugged into the sockets F¹, thereby connecting up the figure A ready for communication. First of all, the conductors c¹, d¹ connect the microphone M with the upper two sockets F¹, and therefore by means of the upper two sockets and two plugs G, the microphone is connected through a low frequency or audio frequency thermionic amplifier T to a loud-speaking telephone instrument or a pair of head telephones H for the attendant's use. The filament and anode batteries for the amplifier T are shown at N. Consequently the attendant, seeing the lamp L¹ illuminated, plugs in the plugs G into the corresponding sockets F¹, and then he can hear what a customer or any other person says in the neighbourhood of the figure A as the speech is reproduced in the instrument H. The attendant then replies, and for this purpose, his microphone O is connected through a low frequency amplifier Q to the lowermost 25 of the plugs G which are plugged in to the lowermost pair of sockets F¹ which are connected by conductors e¹ and f¹ to a loud-speaking telephone S in the head of the figure A. The filament and anode batteries of the 30 amplifier Q are seen at R. Consequently the attendant's reply is given out by the loud-speaker S and appears to come from the mouth of the figure A.

It will be appreciated that the plugs G can be plugged into the sockets F², F³, or F⁴ and then the attendant is connected to reply to anyone speaking to the figure 2, 3, or 4. The conductors c², d², c³, d³, and c⁴, d⁴, are connected to the microphones of the respective figures in a similar way to the connection of the conductors c¹, d¹. Further, the conductors e², f², e³, f³, and e⁴, f⁴, are connected to the respective loud-speakers in the heads of the different figures just as are the conductors e¹, f¹. It will be appreciated without further description that when the plugs G are inserted in the sockets F², F³, or F⁴, conversation can go on between the attendant and anyone speaking in the neighbourhood of the figures 2, 3, or 4.

We claim:—

1. A telephone equipment for selectively connecting a plurality of calling stations with a central station, comprising a device 55 consisting of a representation of a living figure disposed at each of said calling stations, a loud-speaking telephone incorporated in each of said devices, a microphone incorporated in each of said devices, and connecting lines from said telephones and microphones to the central station.

2. A telephone equipment for selectively connecting a plurality of calling stations with a central station, comprising a device 65 consisting of a representation of a living figure

disposed at each of said calling stations, a loud-speaking telephone incorporated in each of said devices, a microphone incorporated in each of said devices, calling means incorporated in each of said devices, and connecting lines from said telephones, microphones, and calling means to the central station. 70

3. A telephone equipment for selectively connecting a plurality of calling stations with a central station, comprising a device 75 consisting of a representation of a living figure disposed at each calling station, a loud-speaking telephone incorporated in each of said devices and in proximity to the mouth thereof, a microphone incorporated in each of said devices, a manually-operated calling means incorporated in each of said devices, and connecting lines from said telephones, microphones, and calling means to the central station. 80

4. A telephone equipment for selectively connecting a plurality of calling stations with a central station, comprising a device 90 consisting of a representation of a living figure disposed at each calling station, a loud-speaking telephone incorporated in each of said devices and in proximity to the mouth thereof, a microphone incorporated in each of said devices, a manually-operated calling means electrically connected to the central 95 station and incorporated in each of said devices, a telephone receiver at said central station, electrical connections adapted to connect said telephone receiver to said microphones, and an amplifying device incorporated in each of said connections. 100

5. A telephone equipment for selectively connecting a plurality of calling stations with a central station, comprising a device 105 consisting of a representation of a living figure disposed at each calling station, a loud-speaking telephone incorporated in each of said devices and in proximity to the mouth thereof, a microphone incorporated in each of said devices, a manually-operated calling means electrically connected to said central station and incorporated in each of said devices, a telephone transmitter at said central station, electrical connections adapted to connect said transmitter to said loud-speaking 110 telephones, and an amplifying device incorporated in said connections to each loud-speaking telephone. 115

6. A telephone equipment for selectively connecting a plurality of calling stations with a central station, comprising a device 120 consisting of a representation of a living figure disposed at each calling station, a loud-speaking telephone incorporated in each of said devices, a microphone incorporated in each of said devices, calling means electrically connected to the central station and incorporated in each of said devices, a telephone receiver at said central station, electrical connections adapted to connect said receiver to 125 130

said microphones, an amplifying device incorporated in said connections to each of said microphones, a telephone transmitter at the central station, further electrical connections adapted to connect said transmitter to said loud-speaking telephones, and an amplifying device incorporated in said further connections to each of said telephones.

In witness whereof we hereunto subscribe our names this 5th day of September, A. D. 10 1929.

EDWARD JONATHAN MARRIOTT.
CYRIL FRENCH.
